Primary Examiner — Barbara Fox*Assistant Examiner* — Lilyana Bekic(74) *Attorney, Agent, or Firm* — Goodwin Procter LLP(57) **CLAIM**

The ornamental design for an indicator for an inhaler, as shown and described.

DESCRIPTION

FIG. 1 is a top view of an indicator for an inhaler showing the new design;

FIG. 2 is a front perspective view thereof;

FIG. 3 is a rear perspective view thereof;

FIG. 4 is a right side view thereof; and,

FIG. 5 is a left side view thereof.

The broken line showing of the inhaler illustrates the environment of the indicator for an inhaler and forms no part thereof.
